UNITED STATES PATENT OFFICE.

THOMAS WILLIAM RIDLEY, OF MIDDLESBROUGH, ENGLAND.

APPARATUS FOR FORMING CONCRETE PILES.

1,101,662.

Specification of Letters Patent.

Patented June 30, 1914.

Application filed January 13, 1914. Serial No. 811,925.

To all whom it may concern:

Be it known that I, THOMAS WILLIAM RIDLEY, a subject of the King of Great Britain, residing at 67 Marton road, Middlesbrough, in the county of York, England, have invented new and useful Improvements in Apparatus for Forming Concrete Piles, of which the following is a specification.

10 Concrete piles are commonly formed by first driving a tubular preparatory pile filling it with concrete and then withdrawing it leaving the concrete in place and it has also been proposed to force the concrete 15 down the preparatory pile by means of a rammer. According to this invention the rammer is operated by a screw and nut. Preferably the top of the screw has fixed to it a worm wheel gearing with a worm 20 revolving in bearings carried by the center pivot of the toggle lever arrangement described in the specification of the United States Patent No. 1,078,000, the worm having fixed to it a chain wheel which is 25 revolved by an endless chain. The stem of the rammer is hollow and has at its top a split nut in which the screw works. When the lower end of the screw reaches the nut the latter is opened and the rammer is either 30 lifted to introduce more concrete into the preparatory pile or else a length is added to the stem of the rammer the nut being thus again raised to the top of the screw.

Figure 1 is a sectional elevation of the apparatus. Fig. 2 is a horizontal section of the split nut and its box on a larger scale. Fig. 3 is a sectional elevation showing the cam grooves for operating the split nut.

40 *a* is the tubular preparatory pile, *b* is the concrete within it and *c* is the rammer.

d is a split nut contained in a box *e* at the top of the rammer.

f is a screw working in the nut and *g* is a worm wheel fixed to the top of the screw.

45 *h* is a worm gearing with the worm wheel and revolving in bearings in a frame *j* fixed to the short link *k*.

50 *l* is a chain wheel fixed to the worm and *m* is an endless chain by which it can be revolved. The bottom of the link *k* rests on the top of the screw *f* and takes its thrust while its upper end is pivoted to one end of

the links *n* whose other ends are connected by the links *o* and *p* to the lifting chain *q* and to the preparatory pile *a*. When the 55 chain *q* is hauled up to withdraw the preparatory pile then as described in the former specification the link connections force the rammer *c* downward and this downward movement of the rammer can according to 60 the present invention be increased or diminished by turning the chain wheel *l*. The halves of the split nut *d* have fixed to them pins *r* which engage with cam grooves *s* in the ends of a strap *t* so that by giving the 65 strap a quarter turn the halves of the nut are separated.

What I claim is:—

1. The combination of a preparatory pile, a rammer inside the pile, a nut and screw, 70 connections between the nut and screw and the pile and rammer, and means for turning the nut and screw relatively to each other to simultaneously draw the pile upward and force the rammer downward. 75

2. The combination of a preparatory pile, means for withdrawing it, a rammer, means operated by the act of withdrawal for actuating the rammer and independently operated adjusting means for varying the motion of the rammer. 80

3. The combination of a preparatory pile, a rammer, a lifting chain, toggle link connections between the chain, the pile and the rammer, a nut and screw in the connections 85 and means for turning the nut and screw relatively to each other.

4. The combination of a preparatory pile, a rammer, a lifting chain, two pairs of links, the links of each pair being pivoted together at one end while their other ends are pivoted respectively to the preparatory pile and to the lifting chain, a third pair of links pivoted together and to the pivots connecting the links of the first pairs, a worm 90 wheel carried by the pivot connecting the links of the third pair, a worm wheel gearing with the worm, a screw fixed to the worm wheel and a nut carried by the rammer and engaging with the screw. 95

THOMAS WILLIAM RIDLEY.
